DESIGN FOR A BOTTLE OR SIMILAR CONTAINER

Louis A. Leppke, Omaha, Nebr.

Application September 18, 1936, Serial No. 64,912

Term of patent 14 years

To all whom it may concern:

Be it known that I, Louis A. Leppke, a citizen of the United States, residing at Omaha, in the county of Douglas and State of Nebraska, have invented a new, original, and ornamental Design for a Bottle or Similar Container, of which the following is a specification, reference being had to the accompanying drawing, forming a part thereof.

Figure 1 is a side elevation showing a flat side of the bottle or similar container embodying my design;

Figure 2 is a side elevation showing one of the corrugated sides of a bottle or similar container embodying my design; and

Figure 3 is a plan view of a bottle or similar container embodying my design.

I claim:

The ornamental design for a bottle or similar container, substantially as shown.

LOUIS A. LEPPKE,
